UNITED STATES PATENT OFFICE.

CHARLES S. OLCOTT, OF MONTCLAIR, NEW JERSEY.

BOOK-HOLDER.

SPECIFICATION forming part of Letters Patent No. 772,473, dated October 18, 1904.

Application filed January 18, 1904. Serial No. 189,647. (No model.)

To all whom it may concern:

Be it known that I, CHARLES S. OLCOTT, a citizen of the United States, and a resident of Montclair, in the county of Essex and State 5 of New Jersey, have invented a certain new and useful Improvement in Book-Holders, of which the following is a specification.

This invention relates to book supports or holders, and has for object the secure holding 10 of a book on a flat or inclined board or surface and the centering of the book whether open or closed with respect to the center of its support.

The invention consists of features of construction and combinations of devices herein-after described, and more particularly pointed 15 out in the appended claims.

One form of the invention is illustrated in the accompanying drawings, forming part 20 hereof, in which—

Figure 1 is a plan view; Fig. 2, a sectional view on the plane 22 of Fig. 1; Fig. 3, a section on the plane 33 of Fig. 1, and Fig. 4 is an elevation also showing a stand for supporting the holder at a suitable height above 25 the floor.

In the drawings the reference *a* marks a board of a suitable size; *b*, parallel dovetailed or equivalent grooves open at one end, 30 and *c* stops that close the open ends of said grooves, said stops being held in place by screws or other suitable means.

The reference *d* marks strips slidable along the grooves *b*, and *e* a tie-piece detachably 35 connected with the slide-strips *d*, as by screws *f*, and which, by preference, is of a shape and size sufficient to form a support for the flexible part of the binding of the book when the last is opened out, as shown in full lines in 40 Fig. 2.

The reference *g* marks a suitable book-cover, of paper, cloth, or the like, in which the sides 45 of the binding *h* are inserted and which serves to protect the book as well as to connect it with the slide formed by the parts *d e* through straps *i*. The straps *i* are connected in any suitable manner with the cover *g* and also with the under side, preferably, of the tie-piece *e*. The tie-piece *e* is shown as being undercut at each end (see line *k* in Fig. 3) to

provide a space for the straps *i*, which are fastened thereto by tacks or screws *l*.

It is noted that the book by the described arrangement is moved in a direction transverse to the length of the book or its flexible back whereby the book may occupy a central position on the board whether open or closed. 55

By the term "book-cover" herein I intend to include not only that form wherein the sides of the binding are inserted in pockets forming part of the cover, but also any arrangement whereby the book and the slide *d e* may be connected to move together. 60

The board *a* may be supported in any suitable manner, as by or on a desk or other article of furniture, or it may be supported on a stand such as that shown in Fig. 4, where the reference *m* marks a tripod through which a rod or tube *n* passes and is held in any position by a set-screw *o* and where reference *p* marks a plate, which is suitably connected with the upper end of the upright *n* and to which the board *a* may be fastened in any suitable manner. 65

In the use of the invention when the book is closed the slide *d e* is to be moved against the stops *c* and when the book is opened out, as in Fig. 2, the said slide *d e* is to be moved against the other ends of the grooves *b*. In each case the center of gravity of the book is 70 over or substantially over the center of the supporting means—in the instance shown the tripod and upright. 75

Changes in arrangement and details may be made without departing from the spirit of 80 this invention. Hence I do not limit myself to the precise form shown in the drawings and above described. 85

What is claimed as new is—

1. A book-holder comprising a board, a book-cover, and a sliding connection between the board and cover moving the book transversely to its length, whereby the book may occupy a central position on the board whether open or closed. 90

2. A book-holder comprising a board provided with parallel grooves, slide-strips in said grooves, a tie-piece connecting said slide-strips, and means for connecting said movable parts with the book. 95

3. The combination of a board or support, a slide thereon having a limited motion, and a flexible book-cover connected with said slide, and arranged to hold the book so that 5 said motion is transverse to the length of the book.

4. The combination with a board provided with parallel grooves in its upper face, sliding strips in said grooves, a cross-piece uniting 10 said strips and undercut, a book-cover, and

straps connecting said cover and said cross-piece where undercut.

Signed at New York, in the county of New York and State of New York, this 15th day of January, A. D. 1904.

CHARLES S. OLCOTT.
